UNITED STATES PATENT OFFICE

PERCY CHARLES GIDLEY LAKE, OF LONDON, ENGLAND

LOOSE-LEAF BINDER OF THE FLEXIBLE-THONG TYPE

Application filed September 12, 1928, Serial No. 305,529, and in Great Britain November 8, 1927.

This invention relates to loose-leaf binders of the flexible thong type in which thongs are fixed to one side or cover member of the binder and are attached at their free ends 5 to a cross bar carried by the other side or cover member of the binder, suitable clamping bars being associated with the thongs and the side or cover members, and positioned between the latter, a ratchet bar being 10 fixed to the cross bar and cooperating with suitably carried pawls, for effecting the adjustment of the parts and the retention of the said parts in adjusted position.

According to the present invention, a pivoted spring returned thumb lever is provided 15 on the interior of the side or cover member with which the cross bar is associated, the said lever carrying a spring pressed adjusting pawl which normally engages with the teeth of the ratchet bar, and which when the lever is moved in one direction from its neutral or normal position, is adapted to move the said ratchet bar to tighten the thongs.

20 A spring operated detent pawl is carried by the said cover member and is normally in engagement with the teeth of the ratchet bar, to hold the said ratchet bar in any adjusted position.

25 The detent pawl is provided with a projecting bolt or pin and the thumb lever with a shaped portion adapted to engage with the bolt or pin when the lever is moved from its neutral or normal position in a direction opposite to that for tightening the thongs, and in this manner the detent pawl is raised from engagement with the ratchet bar.

30 A projecting bolt or pin is also carried by the said side or cover member and is adapted to engage the adjusting pawl when the thumb lever is moved in a direction to free the detent lever. By this movement also the adjusting pawl is moved from engagement with the ratchet bar, thus leaving the ratchet bar and parts connected thereto free for movement as desired. The pivoted thumb lever is notched at its free end and is adapted in the neutral position to receive 35 a locking bolt in this notch to hold the lever

from movement. In this position it will be realized that the pawls are in engagement with the notched bar. A shaped recess is provided in the side or cover member enabling the thumb to pass therethrough for 55 the manipulation of the lever.

The clamping bars which are covered on the outside with fiber or a similar substance, are provided with shaped metal plates in which are mounted metal rollers which allow the thongs to pass over them easily and with a minimum of friction.

In the accompanying drawings:—

Fig. 1 represents a plan of a binder with the manipulating part of a pivoted thumb lever shewing through a recess formed in an inside cover of the binder. The clamping bars are shewn partly drawn together. A keyhole is shewn of a lock which secures the pivoted thumb lever. 65

Fig. 2 represents a plan of a metal plate with a metal roller attached, and an elevation of a plate with a metal roller attached, and a horizontal view of a plate with a metal roller attached. 70

Fig. 3 represents a plan of a pivoted thumb lever pressed backward and shewing all pawls raised out of action, to allow free movement of the ratchet bar in either direction. 75

Fig. 4 represents a plan of a binder with the outside part of the cover removed, shewing the clamping bars partly drawn together. 80

The pivoted thumb lever is shewn in connection with two pawls and the ratchet bar.

The lock shoots a bolt into a notch in the pivoted thumb lever, and secures it from unauthorized use. 85

Fig. 5 represents a plan of a binder with the outside part of the cover removed, shewing the clamping bars completely drawn together by means of pressure from a pawl being applied to the ratchet bar, through the manipulation of the pivoted thumb lever. 90

Fig. 6 is a detail perspective view of one of the clamping bars and associated devices. 95

In the drawings, 6 are the thongs fixed at one end to one side member or cover of the binder and attached at the other ends 100

to the cross-bar 7. The thongs are associated with the clamping bars 3 fixed to the side or cover members of the binder. The cross-bar 7 carries a ratchet bar 8. 9 is a thumb lever pivoted to the inside of one of the side or cover members of the binder, a spring 3^a being employed at the pivot tending to keep the thumb lever in the neutral position shown in Fig. 4. The 10 thumb lever has pivoted thereto a pawl 1^a, an extension of the spring 3^a keeping the said pawl normally pressed into engagement with the teeth of the ratchet bar 8. When in the position shown in Fig. 4 the tail of the 15 pawl 1^a comes into contact with a projecting bolt or pin 4^a carried by the side or cover member.

2^a is a spring-controlled pawl pivotally mounted in the side or cover member and 20 normally engaging with the ratchet bar 8. This pawl carries another bolt or pin 4^a and the lever 9 has a wedge shaped projection 9^a adapted in the neutral position shown in Fig. 4 to come into contact with this bolt 25 or pin 4^a.

5^a is a lock carried by the side or cover member, the bolt of which is adapted to engage in a notch in the free end of the lever 9 when the said lever is in its neutral 30 position shown in Fig. 4. 6^a is a key hole for the insertion of a key to operate the lock 5^a. 2 is a recess formed in the inside of the cover of the binder to allow for free manipulation of the pivoted thumb 35 lever 9.

The clamping bars 3 which are covered on the outside with fiber or other similar substance, are provided with metal plates 4 (as shown in Figs. 3 and 6) in which 40 are mounted metal rollers 5 which allow the thongs 6 to pass over them easily and with a minimum of friction.

It should be observed that the spring 3^a which is coiled round its pivot is not sufficiently strong to throw the pawl 1^a out 45 of engagement with the ratchet bar.

The action will be readily understood. When the lever 9 is in the position shown in Fig. 4, if it is desired to further tighten 50 the thongs 6, the lever is moved to the left. This, by the engagement of the pawl 1^a, carries with it the ratchet bar 8, drawing with it the thongs 6. The ratchet bar 8 is held in the position to which it is adjusted 55 by the detent pawl 2^a and the lever 9 is free to be turned by its spring back to the position shown in Fig. 4.

When the lever 9 is moved from its neutral position in the opposite direction, as 60 shown in Fig. 3, free movement of the thongs is permitted, as the bolt or pin members 4^a and 4^d operate to free the pawls 1^a and 2^a from the teeth of the ratchet bar 8.

A binder constructed as above described 65 possesses many advantages, chief among

which may be mentioned the fact that no keys are necessary in order to expand or contract the binder, and the clamping bars being provided with metal rollers, ensures the easy running of the thongs, and adds to their duration of service, owing to the absence of friction. 70

What I claim and desire to secure by Letters Patent of the United States of America is:—

1. In a loose leaf binder of the class described, a construction including a cover member, a plurality of flexible thongs attached at one end to said cover member, a cross-bar attached to the other end of the thongs, another cover member, a clamping bar carried by each cover member, the said clamping bars being connected with the flexible thongs, a ratchet bar carried by the cross-bar, a thumb lever pivotally mounted on the second-mentioned cover member, an adjusting pawl pivotally mounted on the said lever and adapted to engage with the teeth of the ratchet bar, a detent pawl pivotally mounted on the said second named cover member and adapted to engage with the teeth of said ratchet bar, bolt means carried by the said second named cover member and adapted to cooperate with the adjusting pawl to raise the pawl out of engagement with the ratchet bar when the thumb lever is in one position, and other bolt means carried by the detent pawl and adapted to cooperate with the thumb lever to raise the detent pawl out of engagement with said ratchet bar when the thumb lever is in such position. 90

2. A loose leaf binder as claimed in claim 1, in which spring means are associated with the pivot of the thumb lever adapted to hold the lever in a neutral position, and in which the bolts controlling the adjusting and detent pawls are so positioned that a movement of the thumb lever in one direction simultaneously raises both pawls from engagement with the ratchet bar, while a movement in the reverse direction causes the adjusting pawl operatively to engage and move the said ratchet bar, leaving the detent pawl in engagement with the teeth thereof. 105

3. A loose leaf binder as claimed in claim 1, in which the clamping bars are provided with metal plates carrying metal rollers. 110

4. A loose leaf binder as claimed in claim 1, in which the pivoted thumb lever is notched at its free end, the said notch being adapted to receive the bolt of a securing lock. 120

In witness whereof I affix my signature. 125
PERCY CHARLES GIDLEY LAKE.
